UNITED STATES PATENT OFFICE.

HARRY J. HICK, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,168,806.

Specification of Letters Patent.

Patented Jan. 18, 1916.

Application filed June 1, 1911. Serial No. 630,610.

To all whom it may concern:

Be it known that I, HARRY J. HICK, a citizen of the United States, residing at Alliance, in the county of Stark and State 5 of Ohio, have invented certain new and useful Improvements in and Relating to Filing Appliances, of which the following is a specification.

This invention relates to filing appliances 10 adapted to conveniently support and store under appropriate titles or headings papers and the like and permit ready and quick access to said papers or articles and their removal.

15 For the purpose of illustration, I have, in the accompanying drawings, shown and herein described one form of filing appliance embodying my invention.

Figure 1 is a side elevation of a filing 20 appliance embodying my invention. Fig. 2 is a fragmentary side elevation of the holders, a portion of them being reclined. Fig. 3 is a longitudinal sectional view through the holders shown in Fig. 2 and on the line 25 3-3 of Fig. 4. Fig. 4 is a fragmentary front view of the holders shown in Figs. 2 and 3. Figs. 5, 6, and 7 are detail views, Fig. 6 being taken on the line 6-6 of Fig. 5 and Fig. 7 being taken on the line 7-7 30 of Fig. 4. Fig. 8 is a fragmentary side elevation of the holders removed from the casing and ready for storing in a vault. Fig. 9 is a fragmentary plan view of one of the holders. Figs. 10, 11, 12 and 13 are 35 detail views.

In the drawings, 1 indicates a suitable casing. It may be of any preferred or standard form of construction. The casing preferably includes a back 1^a and a desk or base 1^b, the forward portion of which may be composed of transparent material 1^c.

2 indicates a tray slidably mounted in the casing in a plane below the base 1^b. At 2^a, and immediately below the transparent material or plate 1^c, the tray 2 is provided with a suitable index 2^a. The casing 1 may also be provided with one or more drawers 3.

4 indicates as an entirety a series of holders. Each holder comprises a back 4^a and 50 a series of paper holding devices 4^b. These devices are preferably spring operated and removably secure papers or articles to the adjacent face of the back. The devices 4^b may be arranged upon opposite faces of the 55 back and each may carry a heading or other

classifying title for the papers or records to be filed and stored.

Along its lower or hinged end, the metal of the back 4^a may be extended and bent into a hollow bar 4^a' and its edge arranged 60 parallel with and secured to said back. The bar 4^a' serves to strengthen the back from end to end, and coöperates with the bars 4^a' of adjoining holders to close the space between them.

4^c indicates strips extending along the opposite longitudinal edge of each back 4^a and on opposite faces thereof. These strips serve as end walls for each holder and also space the holders from each other. Additional strips 4^c' may be provided on one or both faces of each back 4^a. These strips operate as rubbing and spacing devices for the holders between their opposite faces.

5 indicates a series of pivot blocks or supports, one for each holder, pivotally connected thereto, and also mounted to swing relative to each other. There are preferably two series of blocks 5, arranged near opposite lower ends of the holders. At 4^d each back 4^a and bar 4^a' is cut away to receive 70 a block 5.

5^a indicates an opening extending from end to end of the block. Through this opening extends a pin 5^b, preferably comprising a screw bolt. The outer end of the pin 5^b is mounted in a side plate 4^e, which is carried by the adjacent holder, while its opposite or inner end screw threads into a nut 4^f preferably arranged within the hollow bar 4^a'. The opening 5^a serves as a bearing for the pin 5^b whereby relative movement between the block 5 and adjacent holder may take place. It will be obvious 85 that these parts can be altered and variously modified to produce these results. The walls of the bar 4^a' may be indented, as shown at 4^a'' to secure the nut 4^f in position.

The side plates 4^e are preferably provided with flanges 4^g the lower ends of which 95 operate as stops 4^g' and 4^g'', one of which prevents the swinging or movement of the adjacent holder relative to the block, in one direction, while the other permits it to swing rearwardly a predetermined distance. This last operation is preferably effected by bending the lower free end of the adjacent flange 4^g inwardly slightly, thus making it shorter than the other.

The blocks 5 are preferably of substan-

tially rectangular shape to form flat faces 5' on its opposite longitudinal sides, the purpose of which will later appear. At 5'a' the blocks may be hollowed out to form recesses which receive counter-balancing springs 6, one for each block. Each spring is preferably coiled around the adjacent pin 5'b. One end 6', of the spring lies in engagement with the adjacent wall of the block and its opposite end, 6'b, operatively engages the back 4'a of the adjacent holder. When the series of blocks are arranged in operative position, that is, supported in an inclined position on the base 1'a, (see Fig. 1) as will later be described, the springs 6 operate to swing the holders rearwardly until the stops 4's' engage the walls of the blocks and arrest their rearward movement, the stops 4's' being arranged to arrest the holders when in substantially a vertical position.

5'e indicate hinge lugs or sets of lugs preferably formed integrally with and extending laterally from the opposite lower corners of each block 5'a. These lugs are formed with suitable apertures 5'd, which align with the apertures of adjoining lugs to receive hinge pins 5'e. The lugs 5'e and pins 5'e serve to hingedly connect the blocks or supports together and permit them to swing relative to each other. The blocks 5 may be formed with suitable recesses 5'f to permit the positioning of the blocks relatively close to each other.

35 7 indicates a support for each series of blocks 5. It is mounted on the base 1'b and provided with a suitable recess or socket to removably receive the hinge lug or pin of the block carried by the frontmost holder 2. The support 7 is constructed to permit the reclining of said front holder. The blocks or holder supports 5 being hingedly connected together, serve as the gearing or pivotal connections between the holders, and thus operate, when one or more of them are reclined, to move the lower edges of the remaining holders forwardly. The pivotal connections between the blocks and the holders permit the latter to swing rearwardly when the supporting blocks are inclined or arranged in operative position so that the upper or free ends of the holders will be in stepped relationship. When in this latter position they expose to view eye signals mounted on or near their free ends.

8 indicates paralleling or spacing devices which are preferably provided between the supports or blocks 5. These devices preferably comprise screws fitted to suitable openings in the side walls of the blocks whereby they can be adjusted. One screw is mounted in one side wall of each block and its head engages with the adjacent side wall of the adjoining block. As will be understood the blocks or supports and the piv-

otal connections between them support the hinged ends of the holders slightly spaced from each other, in order that the holders can swing relative to said supports and lie in a normal vertical position with the spacing strips between them in close engagement. Under these conditions, the devices 8 coöperate with the pivots 5'e to maintain the blocks spaced and parallel to each other side by side and the series of blocks in 75 proper alinement, either in the normal inclined position or in the vertical position. As a result of this construction, the pivots for the holders will always lie in a common plane, when arranged in either a normal or 80 a prone position.

9 indicates a device which preferably has the combined functions of guiding the rearmost holder in its up and down movements, the moving of said holder forwardly and backwardly and the locking of the holders in normal position. In order to effect this last operation, it is pivoted to the casing 1 and carries a latch 9'a which engages the frontmost holder. In Fig. 1 the device 9 is 90 shown in locking engagement with the front holder. The dotted lines in the same figure illustrate its position when guiding the rear holder (and those holders in front thereof) upwardly and forwardly. Since this device forms the subject matter of my invention disclosed and claimed in Letters Patent No. 973,195, dated October 18, 1910, further description thereof is deemed unnecessary.

10 indicates a device which prevents pivotal movements of the holders when they are removed from the casing. It preferably consists of a link pivotally connected at one end to the side of one of the end holders 105 (preferably the rear holder) and provided with a notch or slot 10'a at or near its opposite end to receive a pin or screw carried by the opposite or front end holder. The pin 10'a is preferably headed. A binding device 110 10 may be provided on either or both sides of the holders. When the holders are set up in the casing, the link 10 is disconnected from the pin 10'b. The holders are then free to swing into the normal vertical position 115 under the influence of their springs, the link 10 falling by gravity and assuming the position shown in Fig. 1. When the holders are to be removed from the casing, they are first brought to a position substantially perpendicular to the inclination of the supports 5, or they are all reclined to the prone or horizontal position, and then the link is moved to connect its notched end with the pin 10'b. Since the counterbalance springs 125 are under tension to move the holders on their pivots, they have the effect of putting tensile stress on the link 10 so that it cannot normally become disconnected from the pin 10'b.

The operation of the holders may be described as follows: The blocks or supports 5 are arranged in an inclined position and the holders in a vertical position with the rearmost one resting against a stop or abutment 1^a carried by the back 1^a. The holders are normally supported in this position by the springs 6. To operate a holder it is swung forwardly and downwardly. Such operation first moves the holder on its pivot 5^b until its front stop 4^g engages the upper face or edge of the adjacent support (see dotted lines in Fig. 5). Through the engagement of the stop 4^g with the block, the continued movement of the holder causes the block or support to move therewith, the holder and block then swinging together on the pivot of the block with the next forward block, as an axis. In the return of the holder to the normal position its operation is the same; that is, it first swings on its pivot 5^b until the rear stop 4^g engages with the upper face of the adjacent block (see dotted lines in Fig. 5). The holder in its continued movement, acting through such engagement, carries with it its supporting block, the holder and block moving together until they reach the normal position. The holders may be operated separately or in groups. When operated in groups, each holder and its support operate in the manner just described.

To those skilled in the art of making filing appliances of the class described, many alterations in construction and widely differing embodiments and applications of my invention will suggest themselves, without departing from the spirit and scope thereof. My disclosures and the description herein are purely illustrative, and are not intended to be in any sense limiting.

As will be understood from the foregoing description, the supports 5 are normally arranged in an inclined position with the holders in a vertical position, or inclined to the plane in which the supports normally lie, and the stops 4^g are arranged to limit the rearward movement of the holders so that this relative normal position between the supports and holders can be maintained under the influence of the springs which exert their power to maintain the stops 4^g in engagement with their respective supports. The springs are of a size and tension so that when the support 5 for the front holder 2 is mounted in the support 7 and the rear holder is in engagement with or lies against the abutment 1^a, this relative arrangement of the series of supports and holders is effected. When a holder is operated to the prone position, the tension of the spring therefor is overcome by the forward movement of the holder. As the holders are operated one by one, the guide 9 will operate to move the rear holder forwardly, so that the

relative position between the holders and blocks not operated will be maintained at all times.

It will also be understood from the drawings that when the holders and blocks are in the horizontal position, the blocks lie in a vertical plane and the holders at substantial right angles thereto in compact form ready for binding together.

What I claim is:—

1. In a filing appliance, the combination of a series of supports, pivotal connections between the supports, permitting them to swing relatively to each other, and a series of holders each pivotally mounted on and having limited movement relative to an adjacent support during movement from one position to the other.

2. In a filing appliance, the combination of a series of supports, pivotal connections between the supports permitting them to swing relatively to each other, a series of holders each pivotally mounted relative to an adjacent support, and counterbalancing means between each holder and the adjacent support.

3. In a filing appliance, the combination of a series of supports, pivotal connections between the supports permitting them to swing relatively to each other, a series of holders each pivotally mounted on and having movement relative to an adjacent support during movement from one position to the other, and means between each of said holders and the adjacent support therefor for limiting the movement of said holder relative to said support in opposite directions.

4. In a filing appliance, the combination of a series of supports, a series of holders, each pivotally mounted on one of said supports, pivotal connecting means between the supports permitting them to swing relatively to each other, and means permitting each holder to swing a limited distance in one direction relative to the adjacent holder during operation of said holder from one position to the other.

5. In a filing appliance, the combination of a series of supports arranged side by side, means for supporting said supports normally in an inclined position, pivotal connections between the supports, permitting them to swing relatively to each other into a vertical position, and a series of holders each pivotally mounted on and having limited movement relative to an adjacent support, during the operation of said holder, whereby they are arranged normally in stepped relationship to each other.

6. In a filing appliance, the combination of a series of supports arranged side by side, means for supporting said supports normally in an inclined position, pivotal connections between the supports permitting them to

- swing relatively to each other into a vertical position, a series of holders each pivotally mounted on and having movement relative to an adjacent support during the operation of said holder, whereby they are arranged normally in stepped relationship to each other, and abutments or stops for limiting the rearward movement of said holders relatively to said supports.
- 10 7. In a filing appliance, the combination of a series of supports arranged side by side, means for supporting said supports normally in an inclined position, pivotal connections between the supports permitting them to swing relatively to each other into a vertical position, a series of holders each pivotally mounted on and having movement relative to an adjacent support during the operation of said holder, whereby they are arranged normally in stepped relationship to each other, abutments or stops for limiting the rearward movement of said holders relative to said supports, and means tending to swing each holder rearward on its support.
- 15 8. In a filing appliance, the combination of a series of supports arranged side by side, means for supporting said supports in an inclined position, pivotal connections between the supports permitting them to swing relatively to each other into a vertical position, a series of holders each pivotally mounted on and having movement relative to an adjacent support, whereby they are arranged normally in stepped relationship to each other, and means between each of said holders and the adjacent support therefor for swinging the support on its pivot when a holder is operated.
- 20 9. In a filing appliance, the combination of a series of supports arranged side by side, means for supporting said supports in an inclined position, pivotal connections between the supports permitting them to swing relatively to each other into a vertical position, a series of holders each pivotally mounted relative to an adjacent support, whereby they are arranged normally in stepped relationship to each other, and devices carried by each holder for swinging the adjacent support on its pivot when a holder is operated.
- 25 10. In a filing appliance, the combination of a series of holders, a series of supports, one for each of said holders, normally arranged in an inclined position, pivotal connecting means between the supports permitting them to swing relatively to each other, pivots between each holder and its support to permit the holder to swing a limited distance relative thereto during the operation of said holder from one position to the other, and guide means for the rearmost holder.
- 30 11. In a filing appliance, the combination

of a series of supports pivotally connected together and normally arranged in an inclined position, a series of holders each pivotally mounted on one of said supports and arranged normally in a vertical position, and means tending to maintain said holders severally in normal position.

12. In a filing appliance, the combination of a series of supports pivotally connected together and normally arranged in an inclined position, a series of holders each pivotally mounted on one of said supports and arranged normally in a vertical position, means tending to maintain said holders severally in a predetermined position relative to the supports, a base on which the support for the front holder is mounted, and a back against which the rear holder normally rests.

13. In a filing appliance, the combination of a series of supports pivotally connected together and normally arranged in an inclined position, a series of holders each pivotally mounted on one of said supports and arranged normally in a vertical position, means comprising a stop device carried by each holder for limiting the relative movement thereof, and a spring for normally maintaining the adjacent support and stop in engagement.

14. In a filing appliance the combination of a base, a series of pivotally connected together supports comprising a series of blocks normally arranged parallel to each other and supported in an inclined position on said base, a series of holders one for each block, pivotal connecting means between each of said holders and the adjacent block and permitting said holder to swing relative thereto during its operation from one position to the other, inter-engaging means between the blocks and holders for operating the blocks by the operation of the holders.

15. In a filing appliance, the combination of a series of supports arranged normally in an inclined position, a series of holders each pivotally mounted on one of said supports, and having movement relative thereto when said holder is operated from one position to the other, and devices carried by each of said holders arranged to operate the support therefor when one of the holders is operated, but permitting a predetermined relative movement between them.

16. In a filing appliance, the combination of a series of assembled holders arranged normally face to face, and pivoted connecting and supporting devices between the lower ends of the holders comprising a series of blocks or supports to which the holders are pivotally connected and arranged to swing a limited distance relatively thereto when operated from one position to the other, and independent pivotal connecting means between adjoining blocks or supports.

17. In a filing appliance, the combination of a series of assembled holders arranged normally face to face and pivotal connecting and supporting devices between the lower 5 end of the holders comprising a series of blocks or supports to which the holders are pivotally connected and arranged to swing relatively thereto during operation of said holder from one position to the other, independent pivotally connecting means between adjoining blocks, and devices carried by the holders operating to limit the relative movement between each holder and the adjacent block or support.
18. In a filing appliance, the combination of a series of assembled holders arranged normally face to face and pivotal connecting and supporting devices between the lower 10 ends of the holders comprising a series of blocks or supports to which the holders are pivotally connected, independent pivotal connecting means between adjoining blocks, devices carried by the holders operating to limit the relative movement between each 15 holder and the adjacent block, and means normally tending to maintain one of said limiting devices for each holder in engagement with the adjacent block.
19. In a filing appliance, the combination of a series of supports pivotally connected 20 directly together, a series of holders pivoted one to each support, and abutments on the parts for stopping the rotation of the holders in each direction with reference to their 25 respective supports, for requiring the supports to turn part way in each direction when the respective holders are rotated from upright to reclined position and vice versa.
20. In a filing appliance, the combination of a series of holders each provided with a 30 cutaway portion, a support mounted in said cutaway portion, pivots between each support and the adjacent holder permitting the latter to swing relative thereto, pivotal connections between adjoining supports, and means, operated by the holders for swinging the supports on their pivots.
21. In a filing appliance, the combination of a series of holders each provided with a 35 cutaway portion, a support mounted in said cutaway portion, pivots between each support and the adjacent holder permitting the latter to swing relative thereto, pivotal connections between adjoining supports, and means for supporting the supports normally 40 in an inclined position.
22. In a filing appliance, the combination of a series of holders each provided with a 45 cutaway portion, a support mounted in said cutaway portion, pivots between each support and the adjacent holder permitting the latter to swing relative thereto, pivotal connections between adjoining supports, means, operated by the holders for swinging the 50 supports on their pivots, and means between
- each support and the holder carried thereby tending to move the latter relative to said support in one direction.
23. In a filing appliance, the combination of a series of supports, each provided with a 55 pivot pin and formed with a hollowed out portion through which said pin extends, pivotal connections between the supports permitting them to swing relative to each other, means for supporting the supports in 60 an inclined position, a series of holders, each pivotally mounted on the pivot pin of an adjacent support, normally arranged face to face in a vertical position, and a counter-balancing spring surrounding said pivot pin 65 in each support and supporting each holder in normal position.
24. A filing appliance, comprising supporting means, a series of supports, normally 70 arranged thereon side by side and extending in an inclined plane, pivotal connections between the supports permitting them to swing relative to each other and to move into a vertical plane, a holder pivotally mounted on each of said supports, and spacing devices 75 between the supports for holding the pivots of the holders in a common plane in either position of the said supports.
25. A filing appliance, comprising supporting means, a series of supports, normally 80 arranged thereon side by side and extending in an inclined plane, pivotal connections between the supports permitting them to swing relative to each other and to move into a vertical plane, a holder pivotally mounted on each of said supports, and spacing devices 85 between the supports for holding the pivots of the holders in a common plane in either position of the said supports.
26. In a filing appliance, the combination of a series of rectangular shaped blocks adapted to be arranged substantially side by 90 side, means for supporting the blocks normally in an inclined position including pivotal connections between their lower edges permitting them to swing one by one or in 95 groups into a vertical position, a series of holders, each pivotally supported on an adjacent block, and devices mounted on opposite sides of each holder and arranged to engage and operate the adjacent block but permitting predetermined movement of the holder relative to the block.
27. In a filing appliance, the combination of a series of rectangular shaped blocks adapted to be arranged substantially side by 100 side, means for supporting the blocks normally in an inclined position including pivotal connections between their lower edges permitting them to swing one by one or in 105 groups into a vertical position, a series of holders, each pivotally supported on an adjacent block, devices mounted on opposite 110 sides of each holder and arranged to engage and operate the adjacent block but permitting predetermined movement of the holder relative to the block.
28. In a filing appliance, the combination of a series of rectangular shaped blocks adapted to be arranged substantially side by 115 side, means for supporting the blocks normally in an inclined position including pivotal connections between their lower edges permitting them to swing one by one or in groups into a vertical position, a series of holders, each pivotally supported on an adjacent block, devices mounted on opposite 120 sides of each holder and arranged to engage and operate the adjacent block but permitting predetermined movement of the holder relative to the block.
29. In a filing appliance, the combination of a series of rectangular shaped blocks adapted to be arranged substantially side by 125 side, means for supporting the blocks normally in an inclined position including pivotal connections between their lower edges permitting them to swing one by one or in groups into a vertical position, a series of holders, each pivotally supported on an adjacent block, devices mounted on opposite 130 sides of each holder and arranged to engage and operate the adjacent block but permitting predetermined movement of the holder relative to the block.

sides of each holder and arranged to engage and operate the adjacent block but permitting predetermined movement of the holder relative to the block, and means tending to hold one of said devices on each holder in engagement with the adjacent block.

28. In a filing appliance, the combination of a series of rectangular shaped blocks adapted to be arranged substantially side by side, means for supporting the blocks normally in an inclined position including pivotal connections between their lower edges permitting them to swing one by one or in groups into a vertical position, a series of holders, each pivotally supported on an adjacent block, and means engaging with and swinging said blocks on their pivots when the holders are operated but permitting a

predetermined movement of the holders relative to the blocks.

29. A filing appliance, including a series of supports, pivotal connections between the supports permitting them to swing relatively to each other, a series of holders each pivotally mounted on and having limited movement, relative to an adjacent support, a relatively fixed pivotal bearing for one end support of the series, and a guide for the holder of the other end holder thereof.

In testimony whereof I affix my signature, in the presence of two witnesses.

HARRY J. HICK.
